Portland, Maine, a corporation of Maine

Application May 27, 1940, Serial No. 337,501

54 Claims. (Cl. 149—23)

This invention is embodied in a press wherein mechanical means is employed to move one of the platens into co-operative relation to another platen, the latter being hydraulically operated during pressure applying operations upon given pieces of work, and in which electrical controlling means is provided to secure operation of the mechanical means and of the hydraulic means in properly timed relation to each other. In certain kinds of work, for example, where the work pieces are tanned hides or skins, one of the platens will be heated, preferably the upper platen, since application of heat to the surface of the leather is commonly advantageous both in plating and embossing operations upon leather.

It is an important feature of the invention that electrical controlling means is provided to operate the mechanical operating means for one of the platens and also the hydraulic means for the other platen in such manner that initiation of a pressure applying operation is followed by operations of the press in the full automatic cycle during which the press operates repeatedly at regular short intervals to apply light pressure to the hide or skin, the latter being shifted between successive pressure applying operations to complete the treatment on a given skin. During such automatic operation of the press, the skilled operator times his movements to effect without hesitation the introduction and removal of successive hides or skins. This treatment of a tanned skin with a heated platen at light pressure is commonly spoken of as "kiss-plating," and is usually employed in the treatment of relatively low grade skins and of boarded skins of various grades.

When it is desired to employ a more substantial pressure in kiss-plating operations upon light leathers, provision is made for introducing a low range pressure governor in both the hydraulic and electrical circuits of the press so that pressure may be built up to a point regulatable by adjustment of the pressure governor. The electrical circuit also includes a repeating relay for control of the mechanical means operating one of the platens, the arrangement being such that a manual control member may be so manipulated as to initiate repeated operations of the press in the full automatic cycle, thereby expediting treatment of the skins since the operator readily accommodates himself to the periodic opening and closing of the press to shift the work piece, thereby to secure treatment of all parts thereof and to remove and introduce successive pieces of work.

Preferably, and as shown, the press embodies a high range pressure governor as well as a low range pressure governor with means to select one or the other according to the type of work to be done. The arrangement of the electrical means, however, is such that cutting-in of the high range pressure governor results in making the repeating relay ineffective so that the press operates semi-automatically, that is, it opens automatically at the end of the cycle under control of the pressure governor but each cycle must be initiated by proper manipulation of the manual control member in the electrical circuit. It is to be understood, however, that by proper manipulation of a manual control member a pressing operation may be terminated at any time in the judgment of the operator without waiting for the termination of the operation under control of the pressure governor.

Conveniently, the electrical circuit may be made to include two time relays which may be cut in or out of the circuit by the use of selector switches. By the use of one of the time relays it is possible to secure a dwell for a predetermined period while the work piece is subjected to a heated platen at low pressure, the purpose being to heat the surface of the leather as a preliminary to either a plating or an embossing operation at higher pressures. The arrangement of the electrical means is such that cutting-in of the time delay relay for a dwell at low pressure automatically eliminates the repeating relay, with the result that the press can no longer operate in the full automatic cycle. Through the use of the proper selector switch, a time relay may be cut into the electrical circuit to secure the application of maximum pressure, as determined by a high range pressure governor, for a dwell of regulatable length suitable to secure the best results in embossing operations upon light or heavy leathers.

It is also an important feature of this press, from the standpoint of safety, that it may be caused to open at any time through the operation of the regular manual control or by the operation of an emergency button. The arrangement is such that the press may be caused not only to reverse the movement of the platens at any time during the closing operation but also to open again instantly at any time after it has closed. In order that an operator working under piece work rates may not misuse his power to open the press, for example, by interrupting the building up of pressure to the desired maximum, thereby to speed up the operations of the

press, there is provided a gong which will sound if the press be opened while it is still under control of the pressure governor. Where it is desired, however, to leave to the judgment of the operator the amount of pressure and the length of time during which it is applied to the pieces of a given batch of work, the gong may be disconnected by a switch which is normally under lock and key. The press may then be operated by the usual manual control member (such as a foot treadle) to initiate and also to terminate each pressure applying operation.

It is to be understood that various important features of the invention are applicable to a press of the type wherein mechanical means operates one of the platens to close the gap between it and a stationary platen, hydraulic means being also provided in connection with the same movable platen to effect a pressure applying operation. Other features of the invention are also applicable to a press wherein hydraulic means associated with one of the platens operates the latter both to close the gap between the platens and to effect a pressure treatment of a work piece placed between the platens.

In the light of the foregoing brief description of the invention, it will be evident that this press is characterized by marked flexibility since it may be readily adjusted to operate in any one of a number of ways to secure various results on different classes of work. In the full automatic cycle, wherein the press operates repeatedly following a single depression of a treadle or other controlling member, the operator is freed from constant foot operation of the controlling treadle and may give his attention to proper manipulation of work pieces suitable for treatment by regularly recurring pressing operations of short duration, this arrangement being especially advantageous in that the capacity of the press and of the operator are greatly increased. Through control of a switch or of a valve in the hydraulic means, the operator may instantly change the press to one which operates semi-automatically, wherein a manual control member initiates each operation of the press which performs in a predetermined manner and comes to rest automatically. This manner of operating the press assures the operator of greater safety and permits him to take whatever time is required to present the work pieces for each pressure operation. By the operation of a switch, the press may be made to dwell while the work piece is undergoing treatment by a heated platen at low pressure, while another switch may be used to insure a dwell while the work piece is undergoing treatment at maximum pressure. Furthermore, the time that it takes to build up pressure under control of either a low range pressure governor or a high range pressure governor may be readily adjusted through proper manipulation of a control member associated with a radial pump provided for securing the desired pressure in the hydraulic circuit. With all the adjustments mentioned, it is possible to suit the press for treatment of different kinds of hides and skins according to methods commonly practised in tanneries of this country. For instance, the semi-automatic cycle operation of the press appears suitable particularly for embossing and for the general run of smooth plating, while the full automatic cycle is especially suitable for kiss-plating of light skins after boarding.

These and other important features of the invention and novel combinations of parts will now

be described in detail in the specification and then pointed out more particularly in the appended claims.

In the drawings:

5 Fig. 1 is a view in side elevation of a press showing one embodiment of the invention;

Fig. 2 is a front view, partly in section, of the press shown in Fig. 1;

Fig. 3 is a detail of a check valve;

Fig. 4 is a detail of a valve arrangement;

Fig. 5 is a detail of the pump;

Fig. 6 is a diagram showing relative time operation of three limit switches;

15 Figs. 7 and 8 are sectional views of a three-way valve showing a movable valve member in two different positions;

Figs. 9 and 10 are sectional views of a two-way valve showing a movable valve member in different positions;

20 Fig. 11 shows in side elevation a rotary radial piston-pump provided to furnish a pressure medium for the press operations;

Fig. 12 is a more or less diagrammatic view of the pump, the press cylinders, and the hydraulic circuit;

25 Fig. 13 is a sectional view of a regulating valve shown in the line in Fig. 12;

Fig. 14 is a sectional view of a magnetic brake and clutch;

30 Fig. 15 is a sectional view of a valve for cutting a low range pressure governor into or out of the hydraulic circuit; and

Fig. 16 is a diagrammatic representation of electrical circuits for operating the press.

35 In the illustrated embodiment of the invention, which is designed particularly for smooth plating and embossing operations upon hides and skins, there is provided an upper platen 70 carried at the forward end of a heavy lever member 71 movable about a pivot at 72 to carry the platen 70 into and out of co-operative relation with respect to a lower platen 73. Preferably and as shown, the upper platen 70 is heated by a steam box or chest 74, in a well-known manner.

40 45 Power means is provided for operating the lever member 71, the said means comprising, in the illustrated construction, a pulley 75 arranged to be driven constantly from any suitable source of power, a clutch 76 and a brake 77 (Fig. 14) being provided under electrical control respectively to connect and disconnect the pulley with respect to a shaft 78.

50 55 As shown, a pinion 79 fast on the shaft 78 is in mesh with a large gear 80 secured to a shaft 82 which includes a crank to operate a link 83 pivotally connected to a toggle 84, 84a to operate the lever member 71, it being understood that straightening of the toggle 84, 84a moves the upper platen 70 into co-operative relation with the lower platen 73, while breaking of the toggle 84, 84a effects separating movement of the two platens. Movement of the platen 70 by the described mechanical means has the effect of opening and closing a gap between the platens, suitable for the introduction and removal of work pieces between pressure applying operations.

60 65 70 As shown, the lower platen 73 is carried by two rams or pistons 85 (Figs. 1 and 2). It will be readily understood, however, that either a large or a small hydraulic press may make use of only one hydraulic ram or piston for operating the lower platen. Each piston is movable in a well fitting cylinder 86, the usual U-packing such as that shown at 87 being provided to minimize the escape of the pressure medium under the

very high pressures to which it is subjected in this press. Preferably each piston 85 is supported yieldingly by a spring 88 (Fig. 2), it being one of the purposes of the spring to insure good contact of both upper and lower platens with a work piece placed on the lower platen, the arrangement being such as to accommodate the press to work pieces within a relatively wide range of thicknesses, sufficient, for instance, for all thicknesses of leather. Preferably, and as shown, the lower platen yields downwardly to a slight extent when the upper platen engages the work piece on the lower platen. When the press is open, the hydraulic circuit may be so adjusted that the pressure medium may be under pressure just sufficient to "float" the pistons or rams 85, one purpose being to speed up the pressure applying operation.

The pressure medium (preferably a suitable oil) is supplied to the cylinders 86 by a constantly running pump shown in side elevation at 90 in Fig. 11. This pump is of the type known as a rotary radial piston pump and capable of furnishing about four gallons per minute. Since the pump is commercially well known, full details thereof are not shown in the drawings. For driving the pump there is provided a shaft 92 carrying a tight and a loose pulley 94, 96, respectively, adapted to be driven from any suitable source of power, a coupling being provided at 98 whereby the pump shaft 100 may be driven from the shaft 92, the speed of the shaft being about 1215 R. P. M. Mounted in the casing of the pump is a manually controllable wheel member 102 (Figs. 5 and 11) which adjusts a member 103 and, according to a well-known construction and mode of operation, determines the stroke adjustment of the radial pistons, the pump being of the type shown in United States Letters Patent No. 1,250,170 granted December 18, 1917, upon application of Hele-Shaw and Martineaux. After adjustment of the wheel 102 the latter may be locked in place by a lock member 104 (Fig. 5).

Located below the pump 90 there is shown a fifteen gallon tank 106 (Fig. 11) for the lubricating oil which conveniently serves as the pressure medium in this case, the quantity being large enough to insure that there is no overheating of the oil. At one end of the tank 106 there is a suction screen 108 covering the inner end of a pipe 110 (Figs. 11 and 12) which conducts the oil to the pump 90, a return discharge pipe being indicated at 112 (Fig. 12). Conveniently the tank 106 is provided with two baffle plates 114 and with an oil level gage 115. It is to be understood that the pump 90 is a constantly running pump with one direction of discharge. Furthermore, control through the wheel member 102 provides for adjustment of the stroke of the pump piston and hence determines the oil capacity of the pump and therefore the time it will take to build up pressure in the piston cylinders 86, there being also an indicator (not shown) which affords an indication to the operator of the stroke setting of the pistons. With this pump, the pressure in the medium under the press pistons 85 may be as high as 3000 pounds per square inch.

Upon reference to Fig. 12 of the drawings, it will be observed that oil from the pump 90 passes through the discharge pipe 120, 121 to both of the cylinders 86 through branch pipes 123, a pressure gage 124 being connected to the pipe 121 to indicate at all times the pressure of the oil in the circuit. For controlling the pressure in the pipe 120, 121, there is provided a three-way valve

125 and also a two-way valve 126, the construction of these valves being shown in detail in Figs. 7 to 10, inclusive. Conveniently, the valve pistons of the valves 125 and 126 are solenoid-operated, as indicated at 127, 128, respectively, in Figs. 12 and 16.

Upon reference to Figs. 7 and 8, it will be observed that, when the movable valve piston 130 in the valve 125 is in its lowered position (Fig. 7), the flow of oil is from the pump discharge pipe 120 to the pipe 121 and thence to the cylinders 86, whereas when the valve piston 130 is in its raised position (Fig. 8), the flow of the oil is from the pump discharge 120 into a pipe 131 which opens into a return pipe 132 leading back to the tank 90.

Upon inspection of Figs. 9 and 10, it will be observed that the construction of the valve 126 is substantially the same as that of the three-way valve 125, the three-way valve shown in Figs. 7 and 8 having been conveniently converted into a two-way valve 126 simply by plugging one of the outlets by a screw plug 133. When the valve piston 134 in valve 126 is in its lower position (Fig. 9), oil entering from the pipe 121 passes through the valve 126 and out through a pipe 135 to the pipe 132 which returns the oil to the tank 106, in which case there is little or no pressure in the cylinders 86. On the contrary, when the valve piston 134 is in its raised position in the valve 126 (Fig. 10), oil entering the valve 126 from the pipe 121 is checked or blocked, with the result that pressure within the pipe 121 and hence in the cylinders 86 may be built up to the maximum pressure for which the press is set.

In order that oil may occupy the space below the piston 85 in each cylinder 86, when the press is open, there is provided a regulating valve 137 (Figs. 2, 4, 12 and 13) operative to offer resistance to the flow of oil from pipe 135 to pipe 132 sufficient to cause and maintain pressure in pipe 121 and pipes 123, during the continued operation of the pump 90, so that not only are the said spaces below the pistons 85 occupied by oil but the pressure may be so adjusted as just to float the pistons 85 in the cylinders 86.

When putting the press in commission, or when refilling after having drained the oil from the press to make repairs, it is necessary to provide for escape of air from the hydraulic circuit. For this purpose an air relief cock 138 is conveniently provided on one of the cylinders 62 as indicated in Figs. 2 and 12.

A check valve 139 is provided between the three-way valve 125 and the pipe 123 leading to the first press cylinder 86, the check valve being so constructed that oil may readily pass toward the cylinders but not in the reverse direction, thus insuring, as far as possible, maintenance of the pressure being built up within the pipe 121. While very high pressure is being maintained in the pipe 121 and in the valves 125 and 126, there is bound to be some leakage with a corresponding drop in the pressure. Such drop in pressure is overcome by pump action operating through the valve 125, the check valve 139 having served to maintain the pressure in the pipe 121 even though oil was being by-passed through the pipes 131 and 132 back to the tank 106. Hence when the dropped pressure is to be restored, the pump has only to bring the pressure up the required amount in the short portion of the pipe 120 between the pump and the check valve 139 in order to build it up to (and beyond) the pressure maintained in the pipe 121 by said

check valve 139. By this arrangement, there is no drop in the pressure in the pipe 121 and press cylinders 86 except that caused by some slight leakage, whereas if there were no check valve 139, there might be quite a drop in pressure in the cylinders 86 at the time of the starting of the pressure buildup to replace leakage loss.

There is shown at 140 (Figs. 2 and 12) a relief valve having a chain connection (Fig. 2) to the lower platen 73. When the press is open, the chain is slack, so that the lower platen would have to rise a predetermined distance beyond the normal before the relief valve would become operative. This prevents lifting of the lower platen to an extent such that damage might result to the press through premature contact of the lower platen with the descending upper platen, which is mechanically operated to a predetermined low position. In case the relief valve 140 is operated, liquid is discharged through pipe 141 to an outside container (not shown). For further details of this valve mechanism reference should be had to Patent No. 1,115,013, granted upon application of F. Perkins.

In the operation of the press in embossing hides or skins, there is, during the first stage, a relatively small pressure on the piece of leather being treated, this being due to the fact that, at the time the upper platen descends into contact with the work piece, there is a certain definite pressure in the pressure medium to float the pistons in their cylinders. At this stage, the piston valve 130 of valve 125 is in lower position (Fig. 7), whereby the pressure medium is passing through valve 125 by way of pipes 120, 121, and through valve 126 and by way of pipe 135 to the pipe 132 to return to tank 106. As stated above, pressure in the hydraulic circuit at this stage is due to the regulating valve 137, which is a well-known commercial unit commonly designated a back-pressure valve. This will be clear upon inspection of Fig. 13, wherein the valve 137 is shown to comprise a valve piston 137^a having a head 137^b which may be seated in a countersunk opening at 141 to close the valve against movement of oil from pipe 135 to pipe 132. However, by means of a small pipe 143, the pressure medium enters the bottom of the regulating valve 137 and, because of the large area of a flexible wall or diaphragm 145, the pressure (which is the same as in the pipe 135) lifts the valve head 137^b, against the pressure of a regulatable spring 147, from the seat 141 and thus permits restricted flow of the pressure medium from pipe 135 to pipe 132, whereby a back pressure is produced in the cylinders 86, just sufficient to lift the pistons 85 with the aid of the springs 88 and to maintain the latter in floating condition. The weight of the lower platen and pistons is sufficient to compress the springs 88 (Fig. 2). On the other hand, the back pressure in the hydraulic medium, due to the valve 137, counterbalances a definite (but regulatable) part of such weight so that the springs 88 are enabled to lift these parts to a definite position, for instance, to a position such that the lower platen is contacted and forced downwardly by the upper platen as the latter reaches its lowest position. This results in "jumping" the pressure on the work piece at the very beginning of a pressure applying operation.

In other words pressure on the leather is caused, in this first stage, by the mechanical

lowering of the upper platen 70 into contact with the leather on the lower platen 73, the upper platen moving to a predetermined position and thus forcing downwardly the lower platen against oil in the cylinders 86. It is to be understood, however, that back pressure in the pipe 135 (and hence in the piston cylinders 86) may be eliminated by adjusting a manually operable stop 149 upwardly to a position where it lifts the diaphragm 145 and the piston 137^a upwardly to a position where the head 137^b is lifted to offer no obstruction to the flow of oil from pipe 135 to pipe 132. In that case, there will be no back pressure in the pipe 135 and in the cylinders 86.

In the second stage, pressure is being built up in the hydraulic circuit, including the piston cylinders 86. During this stage the piston 130 in valve 125 is in lowered position (Fig. 7) so that oil passes from the pipe 120 through the check valve 139 (Figs. 3 and 12) to the pipe 121, while at the same time the valve piston 134 in the valve 126 is in raised position (Fig. 10) thereby blocking the flow of oil to pipe 135. Hence, pressure is built up in the pipes 121 and 123 and the cylinders 86 to a point predetermined beforehand (for example, by the use of a pressure governor), although it is also under the control of the operator, as will hereinafter be pointed out. In this stage, during which pressure is built up, the length of time involved in arriving at maximum pressure may be predetermined (as indicated above) by manual adjustment of the member 102 (Figs. 5 and 11) which controls the stroke adjustment of the pump.

In the third stage, pressure is maintained in the piston cylinders 86 for a predetermined period, during which the piston 130 in the valve 125 is moved to and maintained in its raised position (Fig. 8) so that the oil is by-passed through the pipes 131 and 132 back to the tank 106, while pressure is held in the pipes 121 and 123 by the check valve 139 and by the valve 126 in which the piston 134 is in its raised position (Fig. 10) thus blocking the escape of oil to the pipe 135. After a period of time which may be predetermined (although it may be terminated at the will of the operator), the valve piston 134 in valve 126 moves to its lowered position (Fig. 9) thereby connecting pipe 121 with pipe 135 whereby the pressure instantly drops substantially to zero and the oil may return through the pipe 132 to the tank 106. This movement of valve piston 126 terminates stage 3 and initiates stage 4.

It will be noted that, in this stage 4, both valves 125, 126 have their valve pistons so positioned that oil may flow freely through them and through pipes 121 and 135 to the return pipe 132 back to the tank 106. This stage 4, which comes at the end of the pressure applying operation corresponds also to stage 1, except that the pressure in the press cylinders is approximately at zero. Another difference is that, in stage 4 after the release of pressure in the hydraulic circuit, the upper platen 70 is moved upwardly so that the treated piece of work may be readily removed and another piece substituted therefor. On the other hand, stage 1 begins with the lowering of the platen 70 to engage a piece of work on the lower platen 73, after which pressure is built up back of the lower platen to treat the work piece to a pressure operation.

There are provided in the hydraulic circuit, through suitable connections to a pipe 176, which is a branch from the pipe 121, two pressure governors P and Q. Conveniently, governor P may have a working range between 63 and 470 tons pressure at the platens of the press or from about 410 lbs. to about 3000 lbs. per square inch. Governor Q has a minimum cut-in of about 110 lbs. per square inch and a maximum of about 400 lbs. per square inch, the range being from about 17 tons to about 61½ tons at the platens. The figures given above may be reconciled when it is understood that the pistons in the illustrated press are 14 inches in diameter and the platens are 26 by 54 inches. Since governor Q operates to terminate pressing operations at a lower range than governor P, both governors may be connected to the pipe 176, and hence to pipe 121, when governor Q is to control the press operations. When, however, governor P is to control the press at a selected pressure in the higher range of pressures, the governor Q must be disconnected from pipe 176. For this purpose a manually operable three-way valve 188 (Figs. 12 and 15) is provided to be manipulated by a lever 189 to connect the governor Q to the pipe 176 or, alternatively, to a pipe 191 leading to the tank 106.

With reference to Fig. 14 it will be observed that the clutch 76 comprises annular clutch plates 200 keyed to the hub of the driving pulley 75 rotatably mounted on the shaft 78. Keyed to the shaft 78 is a sleeve member 202 having integral therewith an annular flange 204. Surrounding the sleeve member 202 inside the flange 204 is an annular armature member 206 having a screw threaded periphery for engagement with a screw threaded surface at 208 on an enclosing annular cup member 210, the latter being constructed and arranged to enclose the flange 204 to which it is splined and to enclose the clutch plates 200 and also other annular clutch plates 212 which are keyed to the inside of the cup member 210. These clutch plates 212 are shown as made of fiber, although they may be of metal with fiber faces, which present frictional surfaces for engagement with the clutch plates 200. Upon energizing the clutch coils one of which is indicated at 214 (in magnet body 215 keyed to the sleeve 202) the armature member 206 is pulled to the left in Fig. 14 with the result that the clutch plates 200, 212 are firmly engaged with each other to clutch the pulley 75 to the shaft through the sleeve 202. Upon deenergizing the coils, the clutch is released by reason of the movement of the armature 206 and parts attached thereto to the right in Fig. 14 through expansion of a number of light springs one of which is shown at 216.

The brake 77 comprises a member 220 which is attached to the machine frame, the member 220 having keyed thereto a plurality of annular friction plates 222, these friction plates being shown as made of fiber throughout, although they may be of metal having fiber faces. In between the members 222, are annular plates 224 which are keyed to a sleeve 226 in turn keyed to the sleeve 202 fixed to the shaft 78. Screwed onto the sleeve 226 is an annular member 228 to serve as a stop against which the plates 222, 224 may be pressed by a plurality of relatively strong springs, one of which is shown at 230. Under the action of the springs 230, an annular armature member 232 is pressed toward the left in Fig. 14 thereby compressing all of the plates 222, 224 with the

result that the shaft 78 is frictionally locked against movement by the brake members in the brake device 77. Upon energizing the brake coils one of which is shown at 234 with a coil shield 235 between it and the armature 232, the latter is drawn to the right in Fig. 14, thus releasing the pressure on the brake plates 222, 224, whereby the brake is disengaged from the shaft. At 238 are shown collector rings of the electrical mechanism, the rings being insulated from the magnet body 215 which carries the clutch and brake coils. Incidentally, brake and clutch adjustment may be secured through proper setting of the threaded members 228 and 206, respectively.

It will be clear that, upon energizing the brake coils the brake is disengaged with respect to the shaft 78 while, upon energizing the clutch coils, the clutch is caused to engage to hold the pulley 75 in driving engagement with respect to the shaft 78. This is the normal operation of the clutch and brake since, in most press operations, the clutch will be engaged and the brake disengaged while a platen is being moved mechanically toward the other platen. On the contrary, the clutch is disengaged and the brake engaged when the platen is in its open position or when it is in pressing relation with respect to the other platen during building up of pressure in a pressing operation. Sometimes, however, both clutch and brake are disengaged thereby permitting the upper platen in the illustrated machine to swing to open position without any driving action on the part of the clutch and shaft. Such operations of the clutch and brake devices will be described more in detail later in this specification.

Control of the press is exercised through a number of manually operable members having electrical connections to the power means for causing relative movement between the upper and lower platens of the press, means being also provided for exercising automatic control of valves in the hydraulic circuit whereby the lengths of time that the leather is subjected to heating at substantially zero pressure and subsequently at maximum pressure may be predetermined. The control referred to is exercised through electrical circuits including various relay switches, time relays, clutch and brake contactors, solenoid contactors, and pressure governors, all obtainable in the open market as well-known electrical units. These latter are shown in Fig. 16 enclosed in rectangular spaces defined by dash lines. Upon reference to Fig. 16, it will be noted that all the coils of the said units are permanently connected to one side of the supply line and that they are energized by completing circuits to the other side of the supply line.

In order to prepare the press for operation, a main switch 140 (Fig. 16) is closed. At this time a limit switch X is operative by reason of the fact that a cam 156 on the shaft 82 of the press was left in a position to close contacts X1 and X2 in limit switch X, at the end of the preceding cycle of operations. Closing of the main switch 140, therefore, results in energizing the coil of a non-repeat relay A whereby contacts A2, A3 and A4 in relay A are closed and contact A1 opened. The current energizing relay A may be traced through the coil in relay A, through normally closed contact W3 in a foot switch W, adapted to be operated by treadle 157 (Fig. 1), thence through contact X2 and normally closed contact V1 in an emergency button V. It will be noted that the closing of contact A4 establishes an electric interlock (through A4 and normally closed

contact H3 in a relay H to be described later) i. e., a shunt circuit around contact W3 in the foot switch W. Hence, depressing the treadle 157 and opening contact W3 does not break the current energizing the relay A.

In order to initiate the closing of the press, the foot switch W (Fig. 16) is closed by means of the treadle 157 whereby contacts W2 and W4 in switch W close while W1 and W3 open. Closing of contact W4 establishes a current through the coil of master relay D (thence through W4, A3, X1 and V1) and thus energizes master relay D whose contacts D1 and D2 close simultaneously. The closing of contact D2 in turn energizes the coil in a brake contactor B, whose contacts B1, B2 and B3 are thus closed, while through the closed contacts D1 and B1 the coil in a clutch contactor C is energized, closing contacts C1 and C2. Thus, the coils of clutch and brake are simultaneously energized whereby the brake is disengaged and the clutch engaged, the crank shaft 82 of the press begins to rotate and the press arms begin to close. Inasmuch as the current energizing the clutch contactor C is dependent on the closing of switch B1 it can be seen that the clutch cannot be energized, i. e., engaged, before the brake coil has been energized, thereby disengaging the brake and thus eliminating undue wear of clutch and brake friction surfaces. Fig. 16 shows that current passes through contacts C1, C2 and B2, B3 into two separate rectifiers 161 and 163 and thence through the clutch and brake magnets.

Shortly after the upper platen of the press has begun its downward motion, a contact Z2 in a second limit switch Z opens while contact Z1 closes. This is due to the rotation of a cam 164 mounted on shaft 82. A timing diagram (Fig. 6) shows the open positions in dotted circles and closed positions in heavy lines of the contacts of the various cam-operated limit switches. The vertical center line in Fig. 6 represents the crank shaft dead center positions for the fully open and fully closed press platen. During almost the full downward motion of the press platen (as seen in Fig. 6) contact Z1 remains closed and is effective to hold the brake contactor B energized, i. e., the brake disconnected independently of master relay D. It is to be understood that the operator is required to hold the foot switch 157 depressed until the closing of the press has been completed. Should the foot switch be prematurely released, the current through W4 energizing the master relay D would be interrupted and the clutch disengaged. However, the brake coil would be held energized, with the brake disengaged through the action of contact Z1, and the crank shaft would be free to rotate. The rocker arms 71 of the press are unbalanced, that is, so weighted as to return the upper platen of the press to open position, if there is no driving or breaking power on the crank shaft. Thus the operator is able, in an emergency, not only to stop the closing of the press immediately but also to obtain opening of the press by the simple expedient of removing his foot from the treadle 157.

As long as the foot treadle remains depressed, the press will continue its closing. At a point somewhat before fully closed position, as indicated in Fig. 6, contacts Y1 and Y2 in a third limit switch Y are closed by the action of a cam 168 also mounted on shaft 82. The closing of contact Y2 is immediately effective to energize the coil in a timing relay N and to start a synchronous motor N5 therein running. A tap on

the coil in relay N provides low voltage current for the motor N5 through the only closed contact N1 and the current may be traced through coil N, or through part of coil N, contact N1 and motor N5 and thence through the normally closed contacts G1, E3, F5, and M4 in respect to rolls G, E, F and M, which will be described later and thence through the contact Y2.

In the meantime the press platen continues its downward motion and, at a point just in advance of fully closed position, the limit switch Z is returned to normal with contact Z1 open and Z2 closed. At exactly dead center, contact X1 and X2 in limit switch X open whereby relays A and D are deenergized, the opening of contacts D1 and D2, of course, drops out relays C and B, deenergizing clutch and brake coils. The clutch is released, the brake becomes effective through spring pressure, and the press stops in closed position. The foot treadle 157 may now be released, returning all contacts in foot switch W to normal, as shown in Fig. 16.

Contact A1 having returned to closed position upon deenergizing the coil in relay A, contact W1, which closes when the foot switch is released, becomes effective to energize the coil in a repeating relay H which causes contacts H1, H2, H4 and H5 to close and contact H3 to open. With the closing of contact H1 an interlock or shunt circuit around A1 and W1 is established holding the coil in relay H energized, regardless of a possible redepression of foot treadle 157, that is, opening of contact W1. Current may be traced through coil in H thence either through A1 and W1 in sequence or through H1, thence through E3, F5, M4 and Y2. The purpose of establishing this current through repeating relay H will be described later.

The time relay N, of course, has remained energized and after the timing motor N5 has counted off the time period for which the relay had been set contact N1 opens, stopping motor N5 and contact N3 closes, energizing solenoid contactor K by current through the coil of contactor K, and thence through N3, G1, E3, F5, M4 and Y2. This causes the contacts K1 and K2 in the contactor K to close, energizing the solenoid 128 which in turn raises piston 134 in the valve 126 thus closing the latter and causing the building up of pressure in the system, as heretofore explained.

In addition to being able to adjust the amount of time required for operation of time relay N, it is possible to eliminate the time dwell altogether by manual closing of the contacts R1 and R2 in a selector switch R. Fig. 16 shows clearly that contact R1 of the selector switch R provides a shunt circuit around the delayed contact N3 of the time relay N, thus allowing the coil in contactor K and the solenoid 128 to become energized immediately upon closing of the contacts in the limit switch Y. Thus, valve 126 closes before the press platen reaches the full extent of its downward motion, thus permitting the jumping of pressure, as previously explained in connection with the regulating valve 137. As heretofore stated, the closing of valve 126 (either previous to the completed closing of the press or after a period of dwell) causes the pressure to rise in the press cylinders 86 and the rate of building up such pressure is determined by the manual stroke adjustment of the pump 90 (assuming a constant speed of the pump) and not by any element of the electrical circuit.

When the hydraulic pressure being built up

back of the valve 126 reaches a predetermined maximum pressure (which may be as great as 3000 pounds per square inch or as little as 400 pounds per square inch), a pressure governor P (Figs. 1, 2, 12 and 15) becomes operative through the swinging movement of a pivoted contact member P3 (Fig. 15) under control of the usual Bourdon tube, which is geared not only to the pivoted contact member but also to the needle of the pressure gage 124. Said contact member P3 will make contact with a high contact H1 (as shown in dotted lines), which is adjustable to determine the pressure (within the range of pressures given above) at which the pressure governor "cuts in" to allow current to flow through the relay coil of the pressure governor. This current may be traced through the resistance member P4 and through the coil of pressure governor P, thence through contact member P3, contacting point H1 and contact Y1 in limit switch Y. Upon energizing the coil in P, contacts P1 and P2 close, P1 forming an interlock, through establishing a shunt circuit around member P3, thereby to hold the pressure governor energized whether or not the contact member P3 maintains contact at H1. Closing of contact P2 results in energizing the coil in a control relay F, thus closing contacts F1, F2, F3 and F4 and at the same time opening contact F5. At this time only two of the contacts will be described, viz., F1 and F4. Closing of contact F4 energizes the coil in a second solenoid contactor L (current through coil of contactor L, G1, E3, M4, Y2), whereby contacts L1 and L2 in the contactor L are closed, energizing the solenoid coil 127. Energizing of this coil results in lifting the valve piston 130 in the valve 125 to its raised position (Fig. 8) thereby by-passing the pressure liquid through the pipe 131 and 132 (Fig. 12) back to the tank 106 for a period of maximum pressure which will be predetermined by the operator through setting of a timing motor M5 in a time relay M. It is to be understood that the piston 134 of valve 126 remains in raised position (Fig. 10) during the whole period of building up and maintaining the maximum pressure.

This time relay M is energized and its timing motor started running through the contact F1 in control relay F. As in the first-mentioned time relay N, here again a tap is provided on the coil of relay M to provide, through a normally closed contact M1, current for timing motor M5; from there and from the coil in relay M the circuit continues through contact F1 in control relay F and Y1 in limit switch Y. Immediately upon energizing the coil in time relay M, an interlock contact M2 closes providing a shunt circuit around F1 and thus holding relay M energized until the current supplied to it is broken by the opening of Y1 in the limit switch Y. The delayed contacts M1, M3 and M4 will operate after the timing motor M5 has completed its preset cycle.

In case there should be leakage of pressure medium past valve piston 134 in valve 128 (Fig. 12) during the time dwell of time relay M, while the maximum pressure is being held in the press cylinders 86 and adjacent pipes, it is possible to have the pressure drop sufficiently to open H1 contact in the pressure governor P to an intermediate position shown by dotted lines between H1 and L0, while the interlock or shunt circuit at P1 in the pressure governor is still effective to energize the coil therein, whereby the pressure governor through its contact P2 remains effective

to maintain the valve 125 in the by-passing position of Fig. 8.

Should pressure in the press cylinders 86 fall very substantially, due to the said leakage, the 5 Lo contact (shown in full lines) within the pressure governor P will be established, in which case the coil of the pressure governor is deenergized, since the circuit established by the new position of the contact member P3 is a short circuit 10 around the coil of the pressure governor. De-energizing of the coil in the pressure governor P opens all of the contacts therein and also in the control relay F and in the solenoid contactor L, the result being that the solenoid operated valve 15 piston 130 drops to its lower or rest position (Fig. 7) and once more operates to direct the pressure medium into the pipes 121 and 123 to build up the pressure therein and in the cylinders 86. This cycle of pressure loss and rebuilding may 20 or may not take place one or more times. The Lo contact is manually adjustable as is the H1 contact, and the two may be brought close enough together to provide a differential of about 70 pounds per square inch on the pistons, thereby providing for a drop of about ten tons in the 25 pressure on the work piece before pressure begins to build up again. When the maximum pressure has been reestablished, the pivoted switch member P3 reaches H1 position in the 30 pressure governor P which again operates through the control relay F and the solenoid contactor L to hold the pressure in the press cylinders. During all this time the timing motor M5 in the time relay M may still be operating to 35 determine the period during which maximum pressure shall be applied to the leather.

When the timing motor M5 in the time relay M effects operation of the delayed action contacts, M1 opens, stopping the timing motor M5. 40 M3 closes and M4 opens. The opening of contact M4 causes solenoid contactors K and L to be deenergized, thereby allowing the valve pistons in both valves 125 and 126 to drop, thus instantly releasing the built-up pressure in the cylinders 86 and reestablishing the normal flow of the pressure medium through pipes 120, 121 and back through pipes 135 and 132 (Fig. 12). Closing of contact M3 establishes a circuit through the coil of master relay D through said contact 45 M3 and through contact Y2 in limit switch Y, thus energizing the master relay D and, in the manner previously described, making the brake inoperative and the clutch operative whereby rotation of the crank shaft to open the press arms is effected. The opening of contact M4 at the 50 same time causes the previously mentioned repeating relay H to become deenergized when the press begins to open. Near the end of the movement of the upper platen to its uppermost position, the cam 156 again closes limit switch X, establishing a current through the coil of relay A, through W3 with interlock through A4 and H3 in sequence, and through X2 and V1 as before, thus preparing the press for the next cycle. Should the operator have neglected to remove 55 his foot from the treadle 157, relay A will not become energized because W3 will then be in open position, and the press cannot be started again until after W3 has been closed again through releasing the foot switch to establish the described current through relay coil A.

At the end of the upward movement of the upper platen the cam 168 opens the limit switch Y, thus deenergizing the coil in master relay D, hence dropping out clutch and brake contactors

C and B with the result that the brake is on, the clutch off, the presses stopped in open position and ready for another cycle.

The time dwell at maximum pressure, controlled by timing motor in relay M is adjustable within the range of the instrument. It is to be understood that both time relays N and M can be commercially procured having a range of from 4 to 40 seconds in two-second intervals. It is to be understood also that instruments of a different range may be substituted therefor, for instance, one commercial timer being operated by a vacuum tube rather than by a synchronous timing motor and having a range of from .6 to 12 seconds, in a stepless adjustment.

I have provided means to eliminate either or both time dwells at the choice of the operator, the time dwell at substantially zero pressure being eliminated, as previously described, through closing of selector switch R. Another selector switch T has been provided having two contacts T₁ and T₂ which are open when the time dwell is desired and a third contact T₃ which is closed in this case. If these three contacts are reversed, they will make effective the three contacts F₂, F₃ and F₅, respectively, in control relay F. In this case the operation of the press will be as described heretofore up to the point where the maximum pressure has been reached and the contact member P₃ and pressure governor P makes contact at the Hi point energizing relay P, whereupon contact P₂ serves to energize the coil in relay F. The contact T₁ in the selector switch T being closed, it forms together with contact F₂ in the control relay F an interlock for the latter through the establishment of a shunt circuit around contact P₂ thus making control relay F independent of the pressure governor and holding it energized until the press has opened at which point opening of contact Y₄ disconnects coil of relay F. The relay F which, in this case is used to control the opening of the press and also to relieve the pressure in the hydraulic system, thus replaces contacts M₃ and M₄ in the maximum pressure time relay M which performed these functions as previously described when a time dwell was warranted. To effect the opening of the press, the master relay D is energized by a current flowing through the coil of this relay, through contact T₂ in the selector switch T and a contact F₃ in the control relay F, thence through limit switch contact Y₂, with the same results that were shown previously when master relay D was energized through the closing of contact M₃ after the time dwell at maximum pressure. The opening of contact T₃ in the selector switch makes normally closed contact F₅ effective to interrupt the currents through both solenoid contactors K and L in the same manner in which, as previously described, M₄ did when the press was opened subsequently to the time dwell at maximum pressure.

In kiss-plating operations, the press is organized to apply a heated platen for a short time and under low pressure to the grain surface of relatively low grade skins and to boarded skins of various grades. In such operations, the skins are treated to a heated platen during the time that it takes to build up the pressure to 25 or 30 tons, for instance, (the range being up to about 60 tons) whereas embossing operations normally involve pressures at about 400 tons and even higher, i. e., at about 2500 lbs. or more per square inch, while smooth plating might be done at pressures ranging from about 150 to perhaps 300 tons.

For kiss-plating, therefore, it is desirable to operate the press rapidly and this may be conveniently accomplished by arranging the power control mechanism in such manner that the press 5 continues to operate cycle after cycle once the operation has been initiated. Besides a pressure governor P, operative in a range of about 63 to 470 tons, there is provided a low pressure governor Q operative at pressures in a range of about 10 17 to 62 tons. As indicated in Fig. 12, a three-way valve 188 is provided to connect or disconnect pressure governor Q with respect to the main line 121 of the hydraulic circuit.

It will be noted that for operating the press 15 in the kiss-plating treatment of skins, the selector switch R is set so as to eliminate the time dwell at substantially zero pressure. However, the selector switch T may remain set at either of its two positions since the time delay at maximum pressure is automatically eliminated by the use of the low pressure governor Q, it being obvious that, with both pressure governors connected to the pipe 121, pressure in the said pipe 121 will never rise above the maximum of the low pressure governor Q.

The operation of the press organized for kiss-plating operations begins in the same manner as explained above for the usual smooth plating operation. Upon depressing the treadle 157 by 20 which switch W4 in foot switch W is closed, the upper platen begins to close, and shortly before it has reached fully closed position the limit switch Y will close, energizing the solenoid contactor K with the result that the valve 126 (Fig. 35 12) closes and pressure begins to build up in the pipe 121 and in the piston cylinders 86. This pressure will act on both pressure governors P and Q. However, since pressure governor Q has a lower operating range than the pressure governor P, a pivoted contact member Q₃ (Fig. 16) in the pressure governor Q will reach its Hi contact before the corresponding contact member in pressure governor P becomes effective. When contact member Q₃ reaches Hi position, the coil 40 in the pressure governor Q will become energized with the result that both contacts Q₁ and Q₂ are moved to closed position. Contact Q₁ in the pressure governor Q forms an electrical interlock (a shunt circuit) in the pressure governor causing the coil therein to remain energized even after the pivoted contact member Q₃ leaves the Hi contact. The other switch Q₂ allows the coil in a second control relay G to become energized. The control relay G has, for the kiss-plating cycle, the same function as the control 50 relay F in the press organized to provide instantaneous opening of the press at maximum pressure, as before described. An electric interlock for holding control relay G energized during the opening stroke of the press has been provided by removing from the pressure governor Q the connecting wire between the upper end of the coil and the Lo contact. This connecting wire is normally furnished in commercial instrument, as 60 shown in pressure governor P. In the absence of such connecting wire in the pressure governor Q there is no short circuiting around its coil when the pressure drops low enough in the pressure governor to allow contact device Q₃ to make contact at Lo. Hence, the coil in Q remains energized thereby also holding the coil of the control relay G energized until the current supply to them is later removed by the opening of limit switch contact Y₁ at the fully opened press position. The control relay G is provided with a

normally open contact G2 which, upon closing, establishes current through the coil of master relay D, through contact G2 and limit switch contact Y2 to energize the clutch and brake coils and thereby effect the opening of the press. At the same time normally closed contacts G1 and G3 open. The function of the latter will be described later. The function of the opening of G1 is to deenergize the solenoid contactor K whereby valve 126 is opened and the built-up pressure in the hydraulic system immediately released through pipes 135 and 132 (Fig. 12).

It will be noted that this same function was performed in the smooth plating or embossing operation of the press by either contact F5 in the control relay F or contact M4 and time relay M. However, either of the last-named contacts performed the additional function of interrupting the current through the coil of repeating relay H. While in the kiss-plating operation, G1 serves to relieve the hydraulic pressure, it is so positioned that it will not interrupt the current which holds repeating relay H energized, and which, irrespective of the operation of G1, may still be traced through coil of relay H, contacts H1, E3, F5, M4, and limit switch contact Y2. Repeating relay H has been energized, as previously described, through the release of the foot treadle 157 by which contact W1 of the foot switch was closed. If the foot switch now remains released relay H will remain energized until the press has fully opened. Shortly before the opening of the press is completed, limit switch contacts X1 and Y2 close again and X2 energizes the coil of relay A through the closed foot switch contact W3, through limit switch contact X2 and contact V1 in the emergency switch V. Contact X1 of the limit switch at the same time serves to hold the repeating relay H energized by current which flows through the coil of relay H, relay contacts H4 and A2 (the latter closed when relay A was energized) selector switch contact R2 and through contacts X1 and V1. Thus it can be seen that the repeating relay H will remain energized not only during the opening stroke of the press but also during the immediately following closing stroke, that is, until limit switch X opens again.

The closing of the press follows immediately upon its opening without even releasing the clutch or energizing the brake because a contact H5 in repeating relay H has become closed and serves to hold the master relay D energized even after limit switch Y2 has opened upon reaching fully open press position. It will be noted from Fig. 16 that contact H5 is arranged in parallel with contact W4 of the foot switch which latter serves to operate the master relay D in the smooth plating or embossing operation. In these previously described operations, however, repeating relay H had been dropped out previously through the opening of either contact F5 or M4, while in the kiss-plating operation relay H has remained energized during the opening stroke of the press and remains so again during the closing stroke.

From this point on, the press will continue cycle after cycle, closing, building up the pressure to the high point H1 on the pressure governor Q, opening and immediately closing again, and so on, until the operator stops it by a second depression of the foot treadle. This redepression of the foot treadle 157 may take place at any time, that is, during the down stroke of the press, during the building up of pressure, or

10 during the opening of the press, and in each case the press will open and stop in its opening position. After this a new cycle of continuous operations may be initiated by holding the treadle depressed for one closing stroke of the press as described above, and then releasing it.

15 In kiss-plating operations the depression of the foot treadle to terminate the operation would probably take place during the opening stroke. It will be remembered that repeating relay H remained energized while the press was opening and also during the closing stroke and hence that a contact H2 in said relay H remains closed. If, during the opening stroke, the foot treadle is depressed, closing the contact W2 in the foot switch W, a current will be established energizing the coil of an emergency relay E and flowing successively through W2, H2, F5, M4 and Y2. The relay E, in addition to an emergency function to be described later, serves to stop the continuous operation of the press by the opening of its contact E3 which interrupts the current flowing through the coil of repeating relay H. It should be mentioned that an interlock is provided for relay E by means of a current flowing through the coil of relay E, a contact E2 therein, and through limit switch contact Y1. Thus even if the foot switch is only momentarily depressed the relay E will remain energized until the press has opened completely and the now open contact E3 will prevent the repeating relay H from becoming energized again. Upon closing of limit switch X near the high position of the upper press platen, the current through relay H does not become reestablished since the contact H4 in said relay H has opened with the deenergizing of relay H and will not close unless relay H is energized by means of contacts A1 and W1. This means then that the press will stop in its fully open position since contact H4 (used to energize master relay D) remains open and a new cycle of operations would have to be started again in the manner described above.

40 45 50 55 60 65 70 75 Should the depression of the foot switch, intended to stop the continuous operation of the press, occur after the press has opened and immediately started on its down stroke, then the relay E will not become effective but even then the press operation will be interrupted immediately. This is due to the opening of switch contact W3 when the foot treadle is depressed. At this time the function of contact H3 in the repeating relay H should be explained. Since, during the kiss-plating operation of the press, repeating relay H remains energized, contact H3 is in open position and contact A4 in relay A cannot serve as an interlock for the latter. Opening of W3, then, drops out relay A, opening contact A3 and deenergizing the master relay D whereby the clutch is deenergized that is, released while, as has been shown previously, the brake coil is held energized (that is, with the brake off) by the action of contact Z1 in the limit switch Z, thus allowing the press arms to swing back to their open position by means of gravity. In consequence of deenergizing relay A, contact A2 has also opened, interrupting the current through repeating relay H so that the press will not start again after it has been returned to open position, as described, or after the foot treadle is released again. Releasing the foot treadle, closes contact W3, thus energizing relay A and making the press ready for the initiation of another continuous operation.

If during the continuously repeated operations

of the press, the foot switch is depressed while the press is closed and the pressure being built up, the coil of relay E is energized, as described above. In this case, in addition to contact E3 opening, whereby the repeating relay H is dropped out, the relay A effects immediate opening of the press, but this is an emergency operation and will be considered later.

If the manually operable selector switch R should be set to the open position, as shown in Fig. 15, thereby providing the time dwell at substantially zero pressure, the repeating relay H will drop out after the press has opened, since the flow of current from its coil to limit switch X is interrupted at the contact R2 of the selector switch. Thus, with this setting of the selector switch R, the press cannot operate automatically cycle after cycle while the treadle 157 is held down but will operate in the same manner as the usual cycle of the press organized for smooth plating or embossing wherein the foot switch has to be released and then again depressed in order to secure successive operations of the press.

It is believed that for certain types of leather or small size skins kiss-plating may be accomplished satisfactorily with pressures no higher than, perhaps, about 15 tons which may be secured, for instance, by the so-called "jumping" of pressure, that is, by the depression of the floating press pistons 85 due to the action of the downwardly moving upper platen. If this is so, then no building up of pressure beyond that reached by "jumping" is necessary and for this type of leather the crank shaft may be kept rotating continuously, the clutch never becoming deenergized, that is, released, either in the open or closed position of the press. As has been pointed out previously, the amount of "jump" pressure reached may be manually adjusted by regulating the pressure of spring 147 (Fig. 11) in back pressure valve 137 (Figs. 11 and 12). This method of operation may be secured by the manual closing of a selector switch S. As will be seen from Fig. 16, this switch S is so arranged as to allow control relay G to become energized upon the closing of a contact Z2 in limit switch Z which, by reference to Fig. 6, will be found to occur practically at fully closed position of the press but having a very slight overlap with the closed position of limit switch X. This enables the control relay G to become energized just before the clutch would be released and the brake applied in the press closed position and without waiting for pressure to be built up in the pressure governor Q. Control relay G, of course, energizes master relay D as in the previously described kiss-plating cycle, (where the pressure was built up in the pressure governor Q) with the result that brake and clutch coils remain energized, that is, the clutch is never released nor the brake applied, and the crank shaft continues right through its dead center position to effect the immediate opening of the press. Reference to Fig. 6 shows that Y2 closed enough ahead of the crank shaft reaching its bottom dead center to allow the valve piston 134 in valve 126 to close at a point where the press arms would still have a small amount of travel before reaching their lowest position so that, due to the action of the press arms on the floating rams, a definite pressure ("jump" pressure) will be produced before valve 126 again opens under the influence of opening contact G1 of the control relay; this latter, of course, takes place at 75

the point where contact Z2 closes. At the same moment G2 also closes and since this occurs just before X1 opens, the coil of master relay D is never allowed to become deenergized, thus holding the clutch on and the brake off continuously. In all other respects this kiss-plating operation with "jump" pressure functions exactly like the before-described kiss-plating operation with built-up pressure, the repeating relay H being energized and remaining energized through the opening and closing strokes of the press as described in connection with the first-described kiss-plating operation.

To recapitulate, the press may be operated at 15 high pressures (ranging from 63 tons upwardly) with or without time dwells at either or both substantially zero and maximum pressures, the selection of the pressure range being made solely by the setting of valve 138 in Fig. 12. With 20 these adjustments the press will operate in what is commonly called a semi-automatic cycle, namely, upon depressing the treadle 157 the press will close during which closing the treadle must be held depressed. After the completed 25 closing the preadjusted pressure buildup with or without time dwells takes place and then the press opens and stops in position. To initiate a second cycle the treadle must first be released and then depressed again.

A second mode of operation may be chosen by 30 reverse setting of valve 138 to cut in pressure governor Q, in which case the pressure range will be from zero to 62 tons, whereof a range of from about 0 to about 15 tons may be obtained 35 by the previously described "jump" pressure while the remainder of the range from about 16 to 62 tons is determined by the setting of pressure governor Q. In the last-mentioned pressure ranges, it is impossible to obtain a time dwell at maximum pressure. The operation of 40 the press in this case is what is commonly termed full automatic after the press has been closed for the first time, that is, the pressure rises to the predetermined point, the press opens and immediately begins closing again without interruption, the operator being allowed just enough 45 time to shift a skin to a new pressing position between the platens or to remove it preparatory to introducing a new skin. Of course, the operator has control over this immediate reclosing 50 of the press since to stop the press all that is required is a depression of foot treadle 157 at any time during the full automatic cycle. It is believed that in the lower pressure ranges a time dwell at substantially zero pressure is not 55 required. However, provision has been made for obtaining it by means of selector switch R. The choice of this time dwell at substantially zero pressure automatically precludes full automatic 60 operation of the press and changes the cycle to a semi-automatic one the same as is obtained when working in the high pressure range above 63 tons.

Certain safety features for the protection of 65 the operator, as well as for the protection of the press itself or the leather to be treated, are incorporated in the illustrated embodiment of the invention. For the protection of the operator, means is provided for interrupting the closing stroke of the press platen at any time, at the same time returning the upper movable platen to its fully open position. It is to be understood that, in the illustrated press construction, the arrangement is such that, if no driving or braking means are applied to the crank shaft, un-

balance of the press arms will swing them into fully open position from a closed position or from one approaching closed position. This constructional feature is made use of in the electrical safety controls herein provided. At any point during the semi-automatic closing stroke of the press arms, i. e. when working in the high pressure range, or during the initial closing in the pressure range up to 62 tons, the operator has two individual means for interrupting this closing stroke. He may release the foot switch by withdrawing his foot from the treadle 151 and thus interrupt the current through the master relay D because of the opening of contact W4 in foot switch W. Alternatively, he may depress the emergency button V which interrupts the same current by opening contact V1 in said button V. Opening of the master relay D, of course, deenergized the clutch while the brake is held energized (disengaged) by means of contact Z1 in limit switch Z, as previously described, allowing the press arms to be returned to their open position by gravity. As said just above, this emergency opening is accomplished by depression of the emergency button as well as by release of the foot switch. In either case, the press will remain in its open position until the foot switch has been released and then redepressed to initiate a repetition of the normal cycle.

In connection with the operation of the press within the low pressure range up to 62 tons and performing the full automatic continuous cycle, it has been explained that depressing the foot treadle while the press is running continuously will terminate the operation of the press and if this occurs during the down stroke of the upper platen, the current through master relay D will be interrupted through the opening of contact A3, non-repeat relay A having been dropped out by the interruption of its current supply through opening of foot switch contact W3. A study of Fig. 16 will show, of course, that the current supply to relay A may as well be interrupted by opening of emergency button contact V1 which at the same time interrupts the current supply to master relay D as well as repeating relay H. Thus, depression of the emergency button V during the full automatic closing of the press arms has the same effect as operation of foot switch W by means of depressing treadle 151, namely, to interrupt the closing of the press and permit the press arms to return to open position by gravity and stop there until a new cycle is initiated in the usual manner.

In addition, another safety feature is provided making it possible to cause instant opening of the press at any time after its closing has been completed, for instance, during the building up of pressure or during the time dwells. It has been shown previously that after the press arms stopped in their closed position relay A was deenergized, closing contact A1 thereof; and, if now the foot switch 151 were released, repeating relay H became energized through the closing of foot switch contact W1, whereafter H remained energized by means of the interlocking contact H1. Energizing relay H closed a contact H2 and the operator can now, in case of emergency, by depressing foot treadle 151, and consequently closing foot switch W2, establish a current through the coil of emergency relay A, thence through W2, H2, F5, M4 and Y2. This is, of course, true for either the semi-automatic or the full automatic cycle of operation because

in either cycle repeating relay H becomes energized by the release of the foot switch after the press is closed. As has been previously pointed out, in the full automatic cycle, this relay H usually remains energized while in the semi-automatic cycle (that is, within the high pressure range) it is dropped out again by the opening of contact F5 or contact M4 of the corresponding control or time relays F and M. When emergency relay E is energized, contacts E1, E2 and E4 close while contact E3 opens. Contact E2 serves as an interlock to hold relay E energized until the press is fully open and contact E3 serves to interrupt current through repeating relay H as well as through time relay N and the solenoid contactors K and L, with the result that any pressure that may have been built up previous to the emergency depression of the foot treadle, is immediately released by the opening of valve 126 (Fig. 12). Contact E4 of the emergency relay at the same time establishes a current through master relay coil D by way of E4 and Y2, thus starting the immediate opening of the press in a manner exactly like the action of either contacts M3 on the time relay M, G2 in control relay G or F3 in control relay F (together with switch contact T2), had the press been allowed to continue its normal cycle. If the treadle 151 is held depressed until after the completed opening of the press arms, the non-repeat relay A will not again become energized upon closing of limit switch F2, thus making it impossible for the crank shaft to continue its rotation after the press is open. The foot treadle must first be released (allowing relay A to become energized) and then again depressed to start a new cycle in the usual manner.

Fig. 16 shows that a contact V2 in the emergency button V is arranged in parallel with the combined contacts W2 and H2, by the closing of both of which the emergency relay E became energized. Thus not only the foot switch but also the emergency button may be used to energize emergency relay E by means of a current through the coil of E through V2, F5, M4 and Y2. It is clear then, that after the press has completed the closing stroke and at any time thereafter until it again begins to open, the action of the press may be immediately interrupted, the pressure of the hydraulic medium relieved, and the press arms opened either by a depression of the emergency button or by a new depression of the treadle which had been released subsequently to the closing of the press.

In order to prevent an operator from shortening the time of dwell at maximum pressure or from working the leather at insufficient pressure by means of the above-described emergency devices, provision has been made to sound a gong 192 or other indicating device every time the press is opened before completing its normal cycle, so that any repetition of this emergency opening will be called to the attention of the supervisor. Current is supplied to this gong 192 through a small transformer J which, in turn, is energized upon operation of the emergency relay E by a current which passes through the primary transformer coil, thence through contact E1 and normally closed contact G3 in control relay G and thence through a selector switch U.

It will be noted that when operating in the high pressure range, that is, in the semi-automatic cycle, the relay E cannot be energized after the press has begun to open because the circuit

through the coil of relay E, which is normally established by closing of emergency contact V2 or foot switch contact W2, is then interrupted either at the contact F5 or contact M4 of the control relay F or time relay M, respectively, either of which has been operated to start the opening of the press. Thus, the emergency relay E has been rendered inoperative when opening of the press arms started, and hence if the emergency button is operated after that time the gong will not ring. In other words, the emergency relay E can become energized and cause the gong or signaling devices 192 to sound only if the emergency button is operated after the press has closed and before the press begins its opening stroke. This of course is the period during which the operator could shorten the time of operation at the expense of the quality of the work if he were not inhibited by the ringing of the gong.

As has been pointed out previously, in connection with the means for interrupting the full automatic operation of the press (in the low pressure range), the emergency relay E may become energized by means of emergency button contact V2 or foot switch contact W2 at any time after the closing of the press and even during the opening stroke of the press. However, in this case the opening of the press is controlled by control relay G and if the emergency relay E is operated (either by means of foot treadle or emergency button) after the press has started to open, that is, after relay G has become operative, the normally closed contact G3 has opened (and remains open until the press has stopped in the open position) thus interrupting the current supply to the primary coil of transformer J. Therefore, in full automatic operation also the gong will only sound if the emergency button (or foot switch) is used during the time of building up pressure and not after the predetermined maximum pressure has been reached and the press begun to open.

It has been possible to use presses, as heretofore constructed, in a manner which allowed the operator to vary the pressure built up during each pressing operation, according to his judgment. Such an operation of the press described in this specification is possible because the press can (as described in connection with an emergency operation) be opened at the will of the operator at any time during the building up of pressure. It is, of course, understood that the amount of pressure acting on the upper platen at each instant may be read from the pressure gage 124 incorporated into the pressure governor P. When it is desired to have the operator use his own judgment as to the amount of pressure to be used in each pressing operation, when plating or embossing hides or skins, the sounding of the gong may be prevented by opening the manually adjustable selector switch U in the line supplying current to the transformer J. Ordinarily the switch U, along with both time relays M and N, as well as selector switches R, S, and T, will be in a box which may be locked so that the foreman or supervisor may decide the type of operation to be performed by the press. The enclosing cases housing the adjustment members of the two pressure governors are also provided with locks. Of course, the treadle 151 controlling foot switch W and the emergency button V are always accessible to the operator.

Having described my invention, what I claim

as new and desire to secure by Letters Patent of the United States is:

1. In a press, an upper platen, a lower platen, one of said platens being movable relatively to the other and one of the platens having a heated work contacting surface, mechanical means operative to cause relative movement of the platens, hydraulic means comprising a piston cylinder and a piston to move the movable platen toward the other platen, a low range pressure governor in the hydraulic circuit, a pump arranged to be continuously operated to circulate a pressure medium through said circuit whereby a work piece engaged by both platens is subjected to heat at a low pressure built up to a selected point under control of said low range pressure governor, and electrical means including said pressure governor and comprising a manually operable member for securing operation of both the mechanical and hydraulic means in timed relation to each other to effect rapidly repeated operations of the press in the full automatic cycle.
2. In a press, an upper and a lower platen one of which is movable with respect to the other to exert a pressure applying operation on a work piece, mechanical means for moving one of the platens toward and from the other platen to open and close a gap between the platens, hydraulic means including a valve for operating one of said platens in a pressure applying operation, electrical means for controlling the operation of both the mechanical means and the hydraulic means in timed relation to each other, and a manually operable member having connections in said electrical means to initiate operation of both the mechanical and the hydraulic means, said electrical means comprising an electrical power unit for said valve in the hydraulic means and electrical controls for said mechanical means so arranged that, upon initiation of pressure applying operations by a single operation of the manually operable member the press continues in full automatic cycle with repeated operations of the press until control of the latter by the electrical means is interrupted.
3. In a press, an upper and a lower platen movable with respect to each other to exert a pressure applying operation on a work piece, mechanical means for moving the upper platen toward and from the lower platen, hydraulic means including a valve for operating the lower platen, electrical means for controlling the operation of both the mechanical means and the hydraulic means in timed relation to each other, and a manually operable member having connections in said electrical means to initiate operation of both the mechanical and the hydraulic means, said electrical means comprising a solenoid contactor for said valve in the hydraulic means and controlling relays for said mechanical means so arranged that, upon initiation of pressure applying operations by a single sustained operation of the manually operable member for a predetermined period in the first pressure applying operation, the press continues in full automatic cycle with repeated operations of the press until control of the latter by the electrical means is interrupted.
4. In a press, a lower platen and an upper platen movable toward and from each other, mechanical means for effecting movement of one of said platens toward the other platen to close the gap between the platens, hydraulic means

including a valve for operating one of the platens to effect a pressure applying operation, a pressure governor connected to said hydraulic means, electrical means including said pressure governor for opening said valve to terminate the building up of pressure in the hydraulic means, said electrical means serving also to control said mechanical means, and a manually operable member having connections in said electrical means to initiate operation of both the mechanical means and the hydraulic means whereby said mechanical means is caused to move one platen toward and from the other platen and said hydraulic means is rendered operative to effect a building up of pressure between said upper and lower platens in timed relation to the mechanical movement of one of them, and said electrical means including a repeating relay so connected as to secure repeated operation of the press in a full automatic cycle when said manually operable member is operated to initiate a pressure applying operation.

5. In a press, an upper and a lower platen, mechanical means for moving one platen toward and from the other platen alternately to close and to open a gap between the platens, said means comprising a power shaft, clutch and brake devices for controlling operations of the shaft, hydraulic means including a valve for operating one of the platens to effect a pressure applying operation, a pressure governor connected to said hydraulic means, electrical means including said pressure governor for opening said valve to terminate the building up of pressure in the hydraulic means, said electrical means having connections to effect operation of the valve to cause building up of pressure in the hydraulic means and said electrical means including controlling means for said clutch and brake devices, and a manually operable member having connections to said electrical means to initiate operation of the press through both the mechanical means and the hydraulic means in timed relation to each other such that one platen moves toward the other platen to cause engagement of a work piece on the lower platen prior to the building up of pressure in the hydraulic means to effect a pressure applying operation, said electrical means including, in addition to said pressure governor, a repeating relay both operative in said electrical means to secure repeated operation of the press in the full automatic cycle following a single movement of said manually operable member for a predetermined period in the first pressure applying operation of the press.

6. A press according to claim 5 in which a limit switch operating in timed relation to said power shaft controls a solenoid contactor for said valve in the hydraulic means to start the building up of pressure therein.

7. In a press, an upper and a lower platen, mechanical means for moving one of said platens toward and from the other platen, said means comprising a power shaft, clutch and brake devices for controlling operation of the shaft, hydraulic means including a valve for operating one of the platens in a pressure applying operation, a pressure governor connected to said hydraulic means, electrical means including said pressure governor for opening said valve to terminate the building up of pressure in the hydraulic means, said electrical means having connections including a solenoid contactor to effect operation of the valve to cause building up of pressure in the hydraulic means and said electrical means includ-

ing a clutch contactor and a brake contactor respectively for said clutch and brake device, and a manually operable member having connections to said electrical means to initiate operation of the press through both the mechanical means and the hydraulic means in timed relation to each other such that one platen moves toward the other platen to cause both platens to engage a work piece resting on the lower platen, prior to the operation of said hydraulic means to effect a pressure applying operation during which pressure is built up in said hydraulic means under control of said pressure governor, said electrical means comprising a repeating relay operative in said electrical means to maintain current in the clutch and brake contactors whereby the clutch remains on and the brake off to secure repeated operation of the press in the full automatic cycle following a single movement of said manually operable member to initiate a pressure applying operation of the press.

8. A press according to claim 7 in which a limit switch operating in timed relation to said power shaft maintained said repeating relay continuously operative to hold a master relay in control of the clutch and brake contactors for full automatic operation of the press.

9. In a press, an upper platen, a lower platen, one of said platens being movable relatively to the other and one of the platens having a heated work contacting surface, mechanical means operative to cause relative movement of the platens, hydraulic means comprising a piston cylinder and a piston to move the movable platen toward the other platen in timed relation to the operation of said mechanical means, a low range pressure governor in said circuit, a pump arranged to be continuously operated to circulate a pressure medium through said circuit, whereby a work piece engaged by both platens is subjected to heat at a low pressure which is built up to a selected low pressure under control of said low range pressure governor, electrical means including said pressure governor and comprising a manually operable member for securing rapidly repeated operations of the press in the full automatic cycle, and means including a regulating valve in the hydraulic circuit to maintain a predetermined minimum pressure against the piston associated with the movable platen, whereby a work piece engaged by both platens is first subjected to heat at a minimum pressure and also to heat at a low pressure built up under control of the low range pressure governor.

10. In a press, an upper platen, a lower platen movable in an upward direction toward the upper platen, one of the platens having a heated work contacting surface, hydraulic means comprising a piston cylinder and a piston to move said lower platen in an upward direction, mechanical means operable in timed relation to said hydraulic means to move one of the platens to close the gap between the platens whereby a work piece on the lower platen is engaged by both platens, a pump arranged to be continuously operated to circulate a pressure medium through said circuit, means including a regulating valve in said hydraulic circuit operative to maintain in the piston cylinder a predetermined minimum pressure such as will just float the piston and the lower platen, whereby the lower platen will yield against said pressure in the piston cylinder when the work piece is engaged by both platens, the effect being also to produce an instantaneous or jump pressure

70 of low degree on the work piece, and means com-

prising a manually operable member for securing rapidly repeated operations of the press in the full automatic cycle.

11. A press according to claim 10 in which a pressure governor is incorporated in the hydraulic circuit, whereby pressure in said circuit may be built up to a predetermined degree substantially above the instantaneous or jump pressure produced by the upper platen in pressing against the lower floating platen.

12. In a press, an upper and a lower platen movable with respect to each other to exert a pressure applying operation upon a work piece, one of said platens having a heated work contacting surface, mechanical means for moving one of the platens toward the other platen to cause both platens to engage a work piece on the lower platen, hydraulic means including a regulating valve and an electrically controlled valve for operating the lower platen, a pump for supplying a pressure medium to said hydraulic means, said regulating valve operating to raise the pressure in the hydraulic means sufficiently to float the lower platen, a pressure governor in said hydraulic means, electrical means for controlling said mechanical means and said hydraulic means including the electrically controlled valve in timed relation such that the last-mentioned valve is closed before the platens engage the work piece on the lower platen whereby the pressure is jumped in the hydraulic circuit and then built up to a point determined by the pressure governor, a repeating relay in the said electrical controlling means, and a manually operable member in said electrical means and operable to initiate a pressure applying operation of the press and thereafter repeated operations of the press in the full automatic cycle.

13. A press according to claim 12 in which a time relay is included in the electrical means to delay the operation of a valve in the hydraulic means thereby to provide a predetermined dwell at substantially zero pressure, during which pressure is not built up in the hydraulic means, cutting-in of the time delay relay being accompanied by elimination of the repeating relay from the said electrical means, whereby a work piece may be subjected to treatment by a heated platen at minimum pressure for a predetermined time or dwell and then to a built-up pressure under control of the pressure governor, in a press conditioned for the semi-automatic cycle following each operation of said manually operable member.

14. A press according to claim 12 in which a selector switch is included in the electrical means to provide, if desired, a shunt circuit around the time relay thereby to eliminate the dwell at substantially zero pressure and concomitantly therewith to restore the said repeating relay and the full automatic cycle, the latter being secured through proper manipulation of said manually operable member.

15. A press according to claim 12 in which a pressure governor is included in both the hydraulic and electrical means and a second time relay included in the electrical means to give a dwell for a predetermined period at a pressure maximum determined by said pressure governor, in a press thus conditioned for the semi-automatic cycle.

16. A press according to claim 12 in which a selector switch is included in the electrical means to eliminate, if desired, the second time relay and therewith the time dwell at maximum pressure, whereby a work piece may be treated to

a heated platen at small pressure for a predetermined period of dwell to be followed by the building up of pressure to a point satisfactory to the operator who then trips the press to terminate the pressure applying operation.

17. In a press, an upper and a lower platen movable with respect to each other to exert a pressure applying operation on a work piece, mechanical means for moving one platen toward and from the other platen, said means comprising a power shaft and clutch and brake devices for controlling the shaft, hydraulic means including a valve for operating one of the platens for a pressure applying operation, electrical means for controlling the operation of both the mechanical means and the hydraulic means in timed relation to each other, a manually operable member having connections in said electrical means to initiate operation of both the mechanical and the hydraulic means, said electrical means comprising an electrical power unit for operating said valve in the hydraulic means and also clutch and brake contactors for the clutch and brake devices, respectively, together with a controlling relay for the last-mentioned contactors, and a repeating relay in said electrical means, all so arranged that, upon initiation of pressure applying operations by appropriate movement of the manually operable member, the press continues in full automatic cycle with repeated operations of the press until control of the latter by the electrical means is interrupted.

18. A press according to claim 17 in which a time relay is included in the electrical means to delay the operation of a valve in the hydraulic means thereby to provide a predetermined dwell at substantially zero pressure, during which pressure is not built up in the hydraulic means, cutting-in of the time delay relay being accompanied by elimination of the repeating relay from the said electrical means whereby a work piece may be subjected to treatment by a heated platen at little or no pressure in a press conditioned for the semi-automatic cycle following each operation of said manually operable member.

19. A press according to claim 17 in which a selector switch is included in the electrical means to provide, if desired, a shunt circuit around the time relay thereby to eliminate the dwell at substantially zero pressure and concomitantly therewith to restore the said repeating relay and the full automatic cycle, the latter being secured through proper manipulation of said manually operable member.

20. A press according to claim 17 in which a pressure governor is included in both the hydraulic and electrical means and a second time relay included in the electrical means to give a dwell for a predetermined period at a pressure maximum determined by said pressure governor, in a press conditioned for the semi-automatic cycle.

21. A press according to claim 17 in which a selector switch is included in the electrical means to eliminate, if desired, the second time relay and therewith the time dwell at maximum pressure, whereby a work piece may be treated to a heated platen at small pressure for a predetermined period of dwell to be followed by the building up of pressure to a point satisfactory to the operator who then trips the press by suitable manipulation of the manually operable member to terminate the pressure applying operation.

22. In a press, an upper and a lower platen, one of said platens being movable with respect

to the other to exert a pressure applying operation upon a work piece supported on the lower platen, mechanical means for moving one of the platens toward the other platen to close the gap between the platens and to engage a work piece. 5 on the lower platen, hydraulic means including a piston cylinder and a piston therein for supporting the lower platen in a floating condition, said hydraulic means including a regulating valve and a valve operative to check the flow of the pressure medium through a part of said hydraulic means whereby pressure will instantaneously develop in said part of the hydraulic circuit and in the piston cylinder when the work piece is first engaged by both platens, this instantaneously or jump pressure between the platens being regulatable by adjustment of said regulating valve electrical means for controlling both the mechanical means and the hydraulic means in timed relation to each other such that operation of the hydraulic means precedes engagement of the work piece by both platens, and a manually operable member to control said electrical means so arranged that operation of the manually operable member is followed by operation of the press in the full automatic cycle during which the press performs repeated pressure applying operations upon a work piece or work pieces introduced by the operator between said platens.

23. A machine according to claim 22 in which the mechanical means for moving one of the platens comprises a power shaft together with electrically operated clutch and brake devices associated with the shaft, and in which a control relay energizes a master relay which keeps the clutch engaged and the brake released throughout repeated operations of the press in full automatic cycle.

24. In a press, an upper and a lower platen movable with respect to each other to exert a pressure applying operation upon a work piece supported on the lower platen, mechanical means including a power shaft for moving the upper platen toward the lower platen to engage a work piece on the latter, a clutch device and a brake device for controlling said shaft, combined mechanical and hydraulic means including a piston cylinder and a piston therein for supporting the lower platen in a floating condition, said hydraulic means including a valve operative to check momentarily the flow of the pressure medium through a part of said hydraulic means whereby pressure will develop in said part of the hydraulic circuit and in the piston cylinder when the upper platen presses the work piece against the lower platen, whereby the work piece between the platens is subjected to a jump pressure, electrical means for controlling the operation of both the clutch and brake devices and the valve in the hydraulic means in timed relation to each other such that operation of the hydraulic means immediately precedes movement of the upper platen to its lowest position in relation to the lower platen, and a manually operable member to control said electrical means, said electrical control means for the clutch and brake devices including also a control relay, all so arranged that operation of the manually operable member is followed by operation of the press in the full automatic cycle during which the clutch device is constantly engaged with respect to said shaft and the brake device disengaged, whereby the press performs repeated pressure applying operations upon a work piece or work

pieces introduced by the operator between said platens.

25. In a press, an upper and a lower platen movable with respect to each other to exert a pressure applying operation upon a work piece supported on the lower platen, mechanical means including a power shaft for moving the upper platen toward the lower platen to engage a work piece on the latter, a clutch device and a brake device for controlling said shaft, hydraulic means including a piston cylinder and a piston therein for supporting the lower platen in a floating condition, said hydraulic means including a regulating valve and a valve operative to check the flow of the pressure medium through a part of said hydraulic means whereby pressure will develop in said part of the hydraulic circuit and in the piston cylinder when the upper platen presses the work piece against the lower platen, electrical means for controlling both the mechanical means and the hydraulic means in timed relation to each other such that operation of the hydraulic means immediately precedes movement of the upper platen to its lowest position in relation to the lower platen, and a manually operable member to control said electrical means, said electrical means including a clutch contact, a brake contactor and a control relay all so arranged that operation of the manually operable member is followed by rotation of said power shaft with the clutch device constantly engaged and the brake device disengaged, whereby operation of the press in the full automatic cycle takes place, during which the press performs repeated pressure applying operations upon a work piece or work pieces introduced by the operator between said platens.

26. In a press, an upper and a lower platen relatively movable with respect to each other to exert a pressure applying operation upon a work piece supported by the lower platen, hydraulic means including valves for operating one of the platens with respect to the other to effect a pressure applying operation, said hydraulic means comprising a regulating valve to secure a minimum pressure approaching zero in the hydraulic circuit, a pressure governor connected to said hydraulic means, electrical means including said pressure governor for controlling said hydraulic means, and a manually operable control member having connections to said electrical means for initiating a pressure applying operation through control of said hydraulic means, said electrical means comprising a time delay relay to provide a dwell substantially at zero pressure after which pressure is built up in the hydraulic means to a point determined by said pressure governor, the press then opening automatically and coming to rest until the manually operable control member is again moved by the operator to initiate another operation of the press.

27. In a press, an upper platen, a lower platen, one of said platens being movable with respect to the other platen and one of the platens having a heated work contacting surface, a hydraulic circuit comprising a piston cylinder and a piston to move the movable platen into pressing relation to the other, means to circulate a pressure medium through said circuit, means including a regulating valve in said hydraulic circuit to maintain a predetermined minimum pressure against the piston associated with the movable platen whereby a work piece engaged by both platens is subjected to heat at a minimum pressure, a

second valve to effect building up of pressure in the piston cylinder to a predetermined maximum, a solenoid for operating the second valve, and electrical means comprising a time relay for energizing the solenoid after a time interval and thus delaying the operation of the last-mentioned valve for a period of time which may be predetermined by the operator thereby securing heat treatment of the work piece at minimum pressure for a predetermined period and thereafter the building up of pressure to a predetermined maximum for a smooth plating or embossing operation.

28. A machine according to claim 27, in which a pressure governor is included in the hydraulic circuit and in the electrical means to terminate the application of heavy pressure at a predetermined regulatable point.

29. In a press, an upper platen, a lower platen movable in an upward direction toward the upper platen, one of said platens having a heated work contacting face, a hydraulic circuit comprising a piston cylinder and a piston to move said lower platen in an upward direction, a mechanical device to exert an upward pressure on said piston, a pump operating continuously to force a pressure medium into said circuit, said hydraulic circuit comprising a valve operative to maintain in the piston cylinder a predetermined minimum pressure such that the pressure medium in co-operation with said mechanical device operates to float the piston and the lower platen, whereby the lower platen will yield when a work piece is engaged by both platens to effect treatment of the work piece by heat at a minimum pressure, a second valve in the hydraulic circuit operable to stop the flow of pressure medium at a point beyond the piston cylinder whereby pressure is built up in said cylinder to a predetermined maximum, and electrical means comprising a time delay relay to delay the operation of the second valve for a predetermined period whereby the work piece is subjected to heat treatment at minimum pressure for a desired period of time as a preliminary to the application of heavy pressure in a smooth plating operation.

30. In a press, a lower platen, a hydraulic circuit comprising a piston cylinder and a piston to operate said lower platen in an upward direction, a spring arranged to exert a yielding upward pressure on said piston and platen, means to circulate a pressure medium through said circuit, a regulating valve in the hydraulic circuit operative to provide in the piston cylinder a predetermined minimum pressure of the pressure medium therein, whereby said pressure medium co-operates with the spring to float the piston and lower platen, an upper platen movable downwardly a predetermined distance such that a work piece on the lower platen is contacted by the downwardly moving upper platen which continues in movement to force the lower platen downwardly against the floating pressure back of the latter, one of the platens having a heated work contacting face so that the work piece is subjected to heat at minimum pressure, a second valve to effect building up of pressure in the piston cylinder to a predetermined maximum, and electrical means comprising a time relay for delaying the operation of the last-mentioned valve for a regulatable period of time, thereby securing heat treatment of the work piece at minimum pressure for a predetermined period as a preliminary to the application of heavy

pressure in a smooth plating or embossing operation.

31. In a press, a heated upper platen, a lower platen movable in an upward direction toward the upper platen, a hydraulic circuit comprising a piston cylinder and a piston to move said lower platen in an upward direction, a spring arranged to press upwardly upon said piston, said hydraulic circuit comprising a valve constructed to maintain in the piston cylinder a predetermined minimum pressure such that the pressure medium in co-operation with said spring operates to float the piston and the lower platen, whereby the lower platen will yield upon pressing a work piece against the upper platen to effect treatment of the work piece by heat at a minimum pressure, a second valve to effect building up of pressure in the piston cylinder to a predetermined maximum, adjustable means for predetermining such maximum, and electrical means comprising a time relay, adjustable within certain limits, for delaying the operation of the last-mentioned valve for a period of time which may be predetermined by the operator thereby securing a preliminary heat treatment of the work piece for a predetermined period before the application of heavy pressure in a smooth plating or embossing operation.

32. A machine according to claim 31, in which a high range pressure governor is included in both the hydraulic circuit and in the electrical means and is operative to terminate heavy pressure on the work piece at a predetermined regulatable point.

33. In a press, an upper and a lower platen relatively movable with respect to each other to exert a pressure applying operation upon a work piece supported on the lower platen, hydraulic means including valves for operating one of said platens toward the other, a high range pressure governor connected to said hydraulic means, a low range pressure governor adapted to be connected to said hydraulic means, electrical means including said pressure governors for controlling said hydraulic means, and a manually operable member connected to said electrical means for initiating operation of said hydraulic means, said electrical means comprising time delay relays and selector switches therefor whereby a time delay may be provided for at substantially zero pressure at the beginning of the building up of pressure in said hydraulic means or for a time dwell at substantially maximum pressure in the operation of the press on a given piece of work.

34. In a press, an upper and a lower platen one of which is movable with respect to the other, a hydraulic circuit comprising a piston cylinder and a piston therein for moving the movable platen into pressing relation to the other platen, a valve and a pressure governor both in the hydraulic circuit to control the building up of pressure in the piston cylinder whereby the piston and the platen moved thereby are operated to produce a predetermined maximum pressure on a work piece backed by the other platen, and electrical connections comprising said pressure governor and a time delay relay for controlling said valve to maintain said maximum pressure for a predetermined period of time and then to cause operation of the valve to terminate the period of maximum pressure.

35. In a press, an upper and a lower platen one of which is movable with respect to the other, a hydraulic circuit comprising a piston cylinder and a piston therein for moving the movable

platens into pressing relation to the other platen, a pump adapted to be continuously operable to force a pressure medium through said circuit, a valve located in the hydraulic circuit beyond the piston cylinder on the side away from said pump and operable to stop the flow of the pressure medium, thereby to build up pressure in said piston cylinder whereby the piston and the platen moved thereby operate to produce a predetermined maximum pressure on a work piece backed by the other platen, a second valve operative to admit the pressure medium to the piston cylinder and to by-pass the pressure medium as soon as the maximum pressure has been built up in the piston cylinder, and electrical means including a time delay relay for controlling said valves to determine the period of operation of the first-mentioned valve in stopping the flow of the pressure medium through the piston cylinder thereby to maintain said maximum pressure for a predetermined period of time and then to cause operation of the valves to terminate the period of maximum pressure and to restore circulation of the pressure medium through said circuit.

36. In a machine according to claim 35, in which a pressure governor is connected in both the hydraulic circuit and in the electrical means and is operative to condition the said second valve to by-pass the pressure medium at a predetermined pressure in the piston cylinder.

37. In a press, an upper and a lower platen at least one of which is movable with respect to the other, a hydraulic circuit including a piston cylinder and a piston for moving the movable platen toward the other platen, a valve in the hydraulic circuit operable to stop the flow of pressure medium in the hydraulic circuit to build up pressure in the piston cylinder to a predetermined maximum, a second valve in the hydraulic circuit operable to pass the pressure medium to the piston cylinder and alternatively to by-pass the pressure medium back to a reservoir, a pressure governor to control the operation of the second valve to terminate the building up of pressure in the piston cylinder at a predetermined point, and an electrical circuit including said pressure governor and electrical power units in connection with the first-mentioned valve and the second valve and also a time delay relay in the circuit of the electrical unit associated with the first-mentioned valve, to control the operations of these two valves, whereby pressure may be built up in the hydraulic circuit to a predetermined maximum and then that maximum retained for a predetermined period.

38. In a press, an upper and a lower platen at least one of which is movable with respect to the other, a hydraulic circuit including a piston cylinder and a piston for moving the movable platen toward the other platen, a pump adapted to be operated continuously to force a pressure medium through said circuit, a valve in the hydraulic circuit operable to stop the flow of pressure medium in the hydraulic circuit to build up pressure in the piston cylinder to a predetermined maximum, a pressure governor adapted to predetermine the pressure in the piston cylinder and adjustable throughout a wide range of pressures, a check valve co-operating with the first-mentioned valve to maintain pressure in that part of the hydraulic circuit which includes the piston cylinder, a third valve in the hydraulic circuit operable to pass the pressure medium to the piston cylinder and alternatively to by-pass the pressure medium back to a reservoir, means to

5 vary the capacity of the pump thereby to predetermine the time required to build up the pressure to maximum in said circuit, and an electrical circuit comprising electrical power units in connection with the first-mentioned valve and the third valve and also an adjustable time delay relay in the circuit of the electrical unit associated with the first-mentioned valve to control the operations of these two valves, whereby pressure may be built up in the hydraulic circuit to a predetermined maximum and then that maximum retained for a predetermined period, the result being that a work piece may be treated to pressure built up either rapidly or relatively slowly and to maximum pressure for a period of time in a relatively wide range.

39. In a press, an upper and a lower platen at least one of which is movable with respect to the other, one of said platens having a heated face, a hydraulic circuit including a piston cylinder and a piston for moving the movable platen towards the other platen, means to circulate a pressure medium through said circuit at a very low or minimum pressure, means to cause both platens to engage a work piece placed between them at said minimum pressure, a valve in the hydraulic circuit operable to stop the flow of pressure medium in the hydraulic circuit to build up pressure in the piston cylinder to a predetermined maximum, a check valve to maintain pressure in that part of the hydraulic circuit which includes the piston cylinder, a third valve in the hydraulic circuit operable to pass the pressure medium to the piston cylinder and alternatively to by-pass the pressure medium back to a reservoir, and an electrical circuit comprising electrical power units associated with said first-mentioned and third-mentioned valves to control the latter, said electrical circuit comprising also two time delay relays one of which determines a delay in the operation of the first-mentioned valve thereby to secure heat treatment of the work piece at minimum pressure for a predetermined period, the other time delay relay being operative to control the first-mentioned valve to cause it to maintain maximum pressure in the hydraulic circuit for a predetermined period, whereby a work piece is treated to heat at minimum pressure for a predetermined period and subsequently to heat at maximum pressure for another predetermined period.

40. In a press, an upper and a lower platen at least one of which is movable with respect to the other, a hydraulic circuit including a piston cylinder and a piston for moving the movable platen toward the other platen, a valve in the hydraulic circuit operable to stop the flow of pressure medium in the hydraulic circuit to build up pressure in the piston cylinder to a predetermined maximum, a check valve to maintain pressure in that part of the hydraulic circuit which includes the piston cylinder, a third valve in the hydraulic circuit operable to pass the pressure medium to the piston cylinder and alternatively to by-pass the pressure medium back to a reservoir, a pressure governor to control the by-passing operation of said third valve, and an electrical circuit comprising solenoids associated with said first-mentioned and third-mentioned valves to control the latter, said electrical circuit comprising also two time delay relays one of which determines a delay in the operation of the first-mentioned valve thereby to secure heat treatment of the work piece at minimum pressure for a predetermined period, the other time

delay relay being controlled by said pressure governor and being itself operative to control the first-mentioned valve to cause it to maintain maximum pressure in the hydraulic circuit for a predetermined period, whereby a work piece is treated to heat at minimum pressure for a predetermined period and subsequently to heat at maximum pressure for another predetermined period.

41. In a press, an upper and a lower platen, mechanical means for moving one platen toward and from the other platen alternately to close and to open the gap between the platens, said means comprising a power shaft, clutch and brake devices for controlling operation of the shaft, hydraulic means for operating one of the platens to effect a pressure applying operation, said hydraulic means including a high range pressure governor, a regulating valve and also an electrically controlled valve, said regulating valve operating to provide a certain minimum pressure in the hydraulic circuit, electrical means having connections to effect operation of the said electrically controlled valve to cause building up of pressure in the hydraulic means, and said electrical means comprising controlling means for said clutch and brake devices, whereby the mechanically operated platen is moved to cause engagement of the platens with a work piece placed on the lower platen, said mechanically operated platen moving to a position where it presses against the other platen, whereby pressure in the hydraulic medium back of one of the platens is jumped, and a manually operable member having connections to said electrical means to initiate operation of the press through both the mechanical means and the hydraulic means in timed relation to each other, said electrical means comprising a time delay relay operative in said electrical means to secure a dwell of the press at the maximum pressure established by said pressure governor.

42. In a press, an upper platen, a lower platen, a hydraulic circuit comprising a piston cylinder and a piston to operate said lower platen, a spring arranged to exert an upward yielding pressure on said piston and platen, a pump operating continuously to circulate a pressure medium through said circuit, a valve in the hydraulic circuit operative to provide in the piston cylinder a predetermined minimum pressure of the pressure medium therein, whereby said pressure medium co-operates with the spring to float the piston and lower platen, mechanical means to move one of the platens toward the other a predetermined distance such that a work piece on the lower platen is contacted by both platens after which the lower platen is forced downwardly against the floating pressure back of it, one of the platens having a heated work-contacting surface, whereby the work piece is subjected to heat at minimum pressure, a second valve in the hydraulic circuit operative to effect building up of pressure therein to a predetermined maximum, and electrical means comprising a time relay to delay the operation of said last-mentioned valve, whereby the work piece is subjected to heat treatment at minimum pressure for a predetermined period of time, and subsequently to pressure at a predetermined maximum.

43. In a press, a lower platen, a hydraulic circuit comprising a piston cylinder and a piston to operate said lower platen, a spring arranged to exert an upward yielding pressure on said piston and platen, a pump operating continu-

ously to circulate a pressure medium through said circuit, a regulating valve in the hydraulic circuit operative to provide in the piston cylinder a predetermined minimum pressure of the pressure medium therein, whereby said pressure medium co-operates with the spring to float the piston and lower platen, an upper platen movable downwardly a predetermined distance such that a work piece on the lower platen is contacted by the downwardly moving upper platen which continues in movement to force the lower platen downwardly against the floating pressure back of the latter, thereby jumping the pressure in the hydraulic circuit, one of the platens having a heated work contacting surface, whereby the work piece is subjected to heat at minimum pressure, mechanical means to move the upper platen into the recited co-operative relation with respect to the lower platen, a high range pressure governor, a second valve in the hydraulic circuit operative under proper control to effect building up of pressure in the hydraulic circuit to a predetermined maximum, means manually operable while the pump is running to vary its capacity thereby to control the period of building up pressure to the said maximum, electrical means comprising a time relay to delay the operation of said last-mentioned valve, whereby the work piece is subjected to heat treatment at minimum pressure for a predetermined period of time, and a second time delay relay in the electrical means to control the length of dwell at maximum pressure on the work piece.

44. In a press, an upper platen and a lower platen both of which are movable toward and from each other and one of which is provided with a heated work contacting surface, mechanical means for moving one of the platens toward the other platen, hydraulic means including a valve for operating said other platen, a low range pressure governor and a high range pressure governor together with means for selectively connecting the low range pressure governor to said hydraulic means, electrical means for causing operation of the mechanical means and the hydraulic means in timed relation to each other, and a manually operable member in said electrical means and operable to initiate a pressure applying operation of the press, said electrical means, when the low range pressure governor is operative, being capable of causing operation of said mechanical and hydraulic means to provide a press operating in the full automatic cycle with repeated operations of the press following a single operation of the manually operable member, whereas, with the high range pressure governor operative in the electrical means, only a single cycle pressure applying operation is secured through each operation of said manually operable member.

45. A press according to claim 44 wherein inclusion of the high pressure governor in the hydraulic circuit conditions the electric means so that the manually operable member must be operated to initiate each complete cycle of a pressure applying operation of a press, whereas inclusion of the low range pressure governor in the hydraulic circuit so conditions the electric means that said manually operable member must be moved to controlling position and maintained in such position for a predetermined period in the first pressure applying operation to initiate the full automatic cycle with repeated operations of the press following such single sustained operation of said manually operable member.

46. In a press, an upper platen and a lower platen both of which are movable toward and from each other, mechanical means for moving one of the platens toward the other platen, hydraulic means including a valve for operating said other platen, a low range pressure governor and a high range pressure governor together with means for selectively connecting the low range pressure governor to said hydraulic means, electrical means for causing operation of the mechanical means and the hydraulic means in timed relation to each other, a manually operable member in said electrical means and operable to initiate a pressure applying operation of the press, said electrical means, when the high pressure governor is operative, being capable of causing operation of said mechanical and hydraulic means for a single pressure applying operation following each operation of the manually operable member, and a limit switch in the electrical means to effect automatic opening of the press, the arrangement of the electrical means being such that, with either said limit switch or the low range pressure governor operative in the electrical circuit, the press will operate in the full automatic cycle following a single operation of said manually operable member.

47. In a press, a lower platen, an upper platen movable toward and from the lower platen, mechanical means for effecting movement of the upper platen, hydraulic means including a valve for operating the lower platen, a low range pressure governor adapted to be connected or disconnected with respect to said hydraulic means, a high range pressure governor connected to said hydraulic means, electrical means including one of said pressure governors for opening said valve to terminate the building up of pressure in the hydraulic means, said electrical means serving also to control said mechanical means, and a manually operable device in said electrical means to initiate operation of both the mechanical means and the hydraulic means whereby said mechanical means is caused to move the upper platen toward and from the lower platen and said hydraulic means is rendered operative to effect a pressure applying operation between said upper and lower platen in timed relation to the mechanical movement of the upper platen, and said electrical means comprising a repeating relay so connected as to secure repeated operation of the press in a full automatic cycle when the low range pressure governor is in the electrical circuit, introduction of the high range pressure governor into the electrical circuit in place of the low range pressure governor having the effect of eliminating the repeating relay so that manipulation of said manually operable device results in only a single semi-automatic cycle of the press for each operation of said device.

48. In a press, an upper and a lower platen movable with respect to each other to exert a pressure applying operation upon a work piece, a pivoted arm carrying the upper platen, said arm being so weighted as to move the upper platen upwardly to open position when free to do so, mechanical means for moving the upper platen toward the lower platen to engage a work piece on the latter, said means comprising a power shaft, a clutch device and also a brake device, hydraulic means for operating the lower platen, electrical means for controlling said mechanical means including the clutch and brake devices and said hydraulic means in timed relation to each other to build up pressure in the

hydraulic means after the upper platen has completed its down movement, and a manually operable member in said electrical means and operable to initiate a pressure applying operation of the press during which the clutch device is at first engaged with respect to said shaft and the brake device disengaged until the upper platen has reached its lowest pressure applying position whereupon the clutch device is disengaged and the brake device is applied to hold the upper platen in position for the pressing operation, release of both the brake device and the clutch device being followed by opening of the press due to upward movement of the upper platen through the effect of gravity on the weighted or unbalanced arm which carries the upper platen.

49. A press according to claim 48 in which the electrical means includes a clutch contactor and a brake contactor to control the clutch and brake devices, respectively, said electrical means having also a master relay to control said contactors.

50. A press according to claim 48 in which the electrical means includes manually operable members, one of which is the manually operable member used to start the press and another is an emergency button, either of which may be depressed or otherwise suitably manipulated to cause release of both the brake device and the clutch device with respect to the power shaft of the machine, whereby the weighted or unbalanced arm carrying the upper platen returns the latter to its upper or open position.

51. In a press, an upper platen, a lower platen, one of said platens being movable relatively to the other, mechanical means operative to cause relative movement of the platens, hydraulic means comprising a piston cylinder and a piston to move one of the platens toward the other platen, a pressure governor in the circuit of the hydraulic means, a pump arranged to be continuously operated to circulate a pressure medium through said circuit whereby a work piece engaged by both platens is subjected to pressure built up to a selected point under control of said pressure governor, and electrical means including said pressure governor and comprising a manually operable member for securing operation of both the mechanical and hydraulic means in timed relation to each other to effect rapidly repeated operations of the press in the full automatic cycle.

52. In a press, an upper and a lower platen one of which is movable with respect to the latter, a hydraulic circuit comprising a piston cylinder and a piston therein for moving the movable platen into pressing relation to the other platen, a high range pressure governor connected to said hydraulic circuit, a low range pressure governor adapted to be connected to said hydraulic circuit, each pressure governor being operative to control the building up of pressure in the hydraulic circuit, electrical means including said pressure governors, a manually operable valve to connect the low pressure governor or both pressure governors to the hydraulic circuit, and a manually operable member to control the said electrical circuit to initiate a pressure applying operation or operations, the arrangement being such that with the low range pressure governor connected to the hydraulic circuit the press will operate in the full automatic cycle while with the high pressure gov-

ernor in said circuit the press will operate in the semi-automatic cycle.

53. In a press, an upper and a lower platen, mechanical means for moving one platen toward and from the other platen alternately to close and to open a gap between the platens, said means comprising a power shaft, clutch and brake devices for controlling operations of the shaft, hydraulic means including a valve for operating one of the platens to effect a pressure applying operation, a pressure governor connected to said hydraulic means, electrical means including said pressure governor for opening said valve to terminate the building up of pressure in the hydraulic means, said electrical means having connections to effect operation of the valve to cause building up of pressure in the hydraulic means and said electrical means including controlling means for said clutch and brake devices, and a manually operable member having connections to said electrical means to initiate operation of the press through both the mechanical means and the hydraulic means in timed relation to each other such that one piston moves toward the other platen to cause engagement of a work piece on the lower platen prior to the building up of pressure in the hydraulic means to effect a pressure applying operation, said electrical means including, in addition to said pressure governor, a relay both 10 15 20 25 30 operative in said electrical means to secure repeated operation of the press in the full auto-

matic cycle following a movement of said manually operable member.

54. In a press, an upper and a lower platen movable with respect to each other to exert a pressure applying operation upon a work piece, a pivoted arm carrying the upper platen, mechanical means for moving the upper platen toward the lower platen to engage a work piece on the latter and then to depress the lower platen, said means comprising a power shaft, a clutch device and also a brake device, hydraulic means acting on the lower platen for resisting the downward movement of the platens to provide a predetermined pressure on the work piece, electrical means for controlling said mechanical means including the clutch and brake devices and said hydraulic means in timed relation to each other, and a manually operable member in said electrical means, said electrical control means for the clutch and brake devices including also a control relay, all so arranged that operation of the manually operable member is followed by operation of the press in the full automatic cycle during which the clutch device is constantly engaged with respect to said shaft and the brake device disengaged, whereby the upper platen repeatedly descends and ascends to perform pressure applying and pressure releasing operations upon a work piece placed between the platens.

GEORGE E. McLAUGHLIN.
